UNITED STATES PATENT OFFICE.

WILLIAM C. BROWN, OF SYRACUSE, NEW YORK, ASSIGNOR TO HUMPHREY GAS PUMP COMPANY, A CORPORATION OF NEW YORK.

UTILIZING HEAT ENERGY.

1,152,394.

Specification of Letters Patent.

Patented Sept. 7, 1915.

Application filed January 31, 1912. Serial No. 674,508.

To all whom it may concern:

Be it known that I, WILLIAM C. BROWN, a citizen of the United States, residing at Syracuse, in the county of Onondaga, State of New York, have invented a new and useful Improvement for Utilizing Heat Energy, of which the following is a specification.

My invention relates to improvements in means for utilizing heat energy especially as applicable to the moving of water, either to raise the same to a higher head or pressure, or to compress air, or otherwise store energy.

My invention is especially applicable to internal combustion engines, pumps and compressors of the general type which are now known in the art as the Humphrey pump or compressor. One of the simplest forms of such a pump comprises, in operative relationship, a combustion, expansion, or power chamber, a play pipe, a discharge, and also a source of liquid supply. The operation of this device, consists in utilizing the expansive force of a primary medium against a column of liquid, with or without an interposing piston, thereby causing an outstroke of the liquid along the play pipe to a greater head or pressure. When the momentum of the outstroke of the liquid is spent the column returns in the play pipe in response to the head or pressure to which it has been driven, and liquid flows back to expel burnt products and to compress a fresh expansible charge.

The object of the present invention is to increase the efficiency, as for example, to give a greater suction or lifting force to the incoming liquid or water.

Where a pump of the class described has a suction lift, it is of course necessary to produce a tendency to vacuum in the play pipe, in order to lift the water to it, and where air or other elastic cushion is used to start the return movement of the water column, the air in this cushion will normally have to expand down to below atmospheric pressure before water will be lifted. This is undesirable in many cases, since it limits the practicability of the pump to very low suction lifts. By using a rigid piston between the water column and the compressed expansible medium, this undesirable condition is prevented and other advantages are secured.

Referring to the drawings, which show merely by way of example, apparatus suitable for effecting my improved invention— Figure 1 is a diagrammatic view of apparatus with my invention applied. Fig. 2 is a vertical section of the part of the apparatus embodying my invention showing two pipes or branches connected with the water supply chamber. Fig. 3 is a vertical section of another form of embodiment, suitable for air compressors.

Similar numerals refer to similar parts throughout the several views.

Fig. 1 illustrates diagrammatically, a usual type of Humphrey pump or compressor with my invention applied thereto. The expansion chamber 4 being provided with the usual inlet and discharge ports. This chamber delivers to the play pipe 5. The other end of the play pipe being the water discharge end, will be described in connection with Fig. 2.

Referring to Fig. 2, 5 indicates a portion of the play pipe toward the water or discharge end of the apparatus. 6 indicates the discharge valves, 7 the air chamber into which the water or other liquid is forced, 8 the discharge pipe, 9 a hollow piston adapted to reciprocate in the air chamber 10, communicating with the supplemental annular air chamber 11 through the ports 12. This piston 9 is connected with the vertical hollow rod 13 which communicates with the interior of piston 9 and projects through the top of the chamber 10 through suitable packing.

It will be understood that with each expansion of an expansible charge or primary medium, at the expansion or power chamber end of the play pipe, a column of liquid is forced outwardly toward the discharge end of the play pipe. This liquid column, coming in contact with the piston 9, will force it upwardly and compress the air in 10 and 11, until the pressure in the play pipe reaches the pressure in the air chamber 7, whereupon the discharge valves 6 will open, permitting the liquid to flow from the play pipe into the air chamber 7, and thence through discharge pipe 8, until the liquid comes to a state of rest, that is, until the momentum of the outwardly moving liquid is expended. The piston 9 due to the

pressure stored above it, now forces the liquid back, causing the return, or instroke, the piston following up until it strikes its seat. The liquid now carried forward by 5 its own momentum will draw liquid through the suction valves 14, into the play pipe. It will thus be seen that the piston prevents the air previously compressed in 10 and 11, from expanding further, hence the formation 10 of a vacuum in the play pipe by the further movement of the liquid column after piston 9 comes to rest.

The suction or intake valves 14 are shown as inclosed in a water supply chamber 28 15 to which pipe 29 delivers. In Fig. 2 two pipes 29 and 30 are shown connected to the chamber 28. The method or means of supplying water to chamber 28 is entirely immaterial to the present invention.

20 The construction of piston 9, while not necessarily hollow, is in this case made hollow in order to make it light for two purposes, one to reduce momentum and the other to make it lighter than the water so 25 that there will be no tendency for water to leak past. The air in the piston also helps the prevention of transfer of heat, the air being a good non-conductor. The piston is also provided with a dash-pot. The hydraulic dash-pot illustrated in Fig. 2 is secured by providing its lower extension of such formation that it cuts off the flow of water between it and the stationary seat 15, just before the shoulder 16 drops onto the 35 seat 15, thereby easing the shock of stopping the piston.

It is obvious that other forms of dash pot could be used, for example, such as shown in Fig. 3.

40 In order to prevent the piston from striking the head an air cushion is also provided at the upper end of chamber 10, which is formed by the upper end of the piston passing and closing the holes 12, before reaching 45 the top of chamber 10, thus shutting off flow of air into the annular chamber 11.

It is frequently desirable to provide 50 means for varying the capacity of the air chamber, or volume of the air cushion. In the drawings are illustrated two means for accomplishing this object.

In Fig. 2 the auxiliary annular chamber 55 11 is adapted to be filled with water to any point up to the openings 12. A glass gage 17 on the outside of the apparatus shows the level of this water, and any suitable means, such as the valve controlled supply pipe 26 and the valve controlled discharge pipe 27, are provided for raising and lowering it at will.

In Fig. 3 means are shown for varying the capacity of the chamber 20, for air or other elastic cushion, comprising the adjustable head 18 between the movable piston 19 and the fixed cylinder head 21. This head 18 is

slidable on piston rod 22 and its position of adjustment is secured by the set-screws 23. Piston rod 22 is also provided with a supplemental piston 24 operating in the dash pot 25.

70 It will be obvious that this means of utilizing an elastic cushion for securing the return movement of the liquid column, without permitting said cushion to expand down to below atmospheric pressure, is 75 equally applicable to compressors, as indicated by Fig. 3.

What I claim is:—

1. The combination of a play pipe for the reciprocation of liquid of sufficient bulk and 80 path of travel to enable it to acquire useful momentum, a chamber connected with the play pipe adapted to contain an expansible medium, a piston separating the liquid from the medium, and a liquid dash-pot pocket 85 between the piston and its seat.

2. The combination of a power chamber, a play pipe and an air chamber connected together for the reciprocation of liquid 90 therein, a piston separating the liquid from the air and having limited movement in the air chamber, and a liquid dash pot pocket between the piston and its seat.

3. The combination of a power chamber, 95 a play pipe and an air chamber connected together for the reciprocation of the liquid therein, a piston separating the liquid from the air provided with a lower extension of reduced diameter having a close fit with the margin of its surrounding seat, so that 100 the liquid is trapped in the pocket formed between the piston shoulder and its seat, toward the end of its downward movement, to form a hydraulic dash pot.

4. The combination of a power chamber, 105 a play pipe and an air chamber connected together for the reciprocation of liquid therein, a piston separating the liquid from the air and having limited movement in the air chamber, and a liquid dash pot pocket between the piston and its seat, said piston so constructed that its weight shall be less than the weight of an equal bulk of water.

5. The combination of a power chamber, 115 a play pipe and an air chamber connected together for the reciprocation of liquid therein, a piston separating the liquid from the air and having limited movement in the air chamber, and a liquid dash pot pocket between the piston and its seat, said piston made of such form or of such material as to reduce its specific gravity, in order to 120 reduce momentum of the piston and also to lessen the tendency of the liquid to leak past.

6. The combination of a play pipe for the reciprocation of liquid, primary actuating means connected therewith, a chamber for an expansible medium, a valve controlled inlet in the play pipe and a piston of lim- 125 130

ited movement operating between the liquid and the expansible medium for limiting the expansion thereof so that the further movement of the liquid due to momentum, shall 5 create a tendency to vacuum to entrain fresh liquid or fluid.

7. The combination of a play pipe for the reciprocation of liquid, primary actuating means connected therewith, a chamber for 10 an expansible medium, a valve controlled inlet in the play pipe and a piston of limited movement operating between the liquid and

the expansible medium for limiting the expansion thereof so that the further movement of the liquid due to momentum, shall 15 create a tendency to vacuum to entrain fresh liquid or fluid, said piston made hollow in order to reduce its momentum, to reduce the tendency of liquid to leak past it and to serve as a non-conductor of heat.
